UNITED STATES PATENT OFFICE.

HENRY M. COLLESTER, OF GARDNER, MASSACHUSETTS.

DESIGN FOR CANE FABRIC.

SPECIFICATION forming part of Design No. 26,551, dated January 19, 1897.

Application filed December 11, 1896. Serial No. 615,408. Term of patent 7 years.

To all whom it may concern:

Be it known that I, HENRY M. COLLESTER, of Gardner, in the county of Worcester and State of Massachusetts, have invented and 5 produced a new and original Design for Cane Fabric, of which the following is a specification.

Reference is to be had to the accompanying drawing, forming a part of this specification, 10 which shows a piece of cane fabric with my design applied.

The leading feature of my design consists in the arrangement of intersecting stripes *a* and *b* of a contrasting color from the body of 15 the fabric, forming parallel rows of cross-shaped figures, and the intersecting stripes *c* of a contrasting color from the body of the fabric and from the stripes *a* and *b* and arranged between the rows of cross-shaped figures. 20

f represents a piece of cane fabric bearing my design, which consists of the arrangement of the intersecting stripes *a* and *b* of contrasting color from the body of the fabric and forming parallel rows of cross-shaped figures. 25 The stripes *c* are arranged between the rows of cross-shaped figures and are of a different or contrasting color from the stripes *a* and *b* and the body of the fabric.

I claim—

The design for cane fabric, as herein shown and described. 30

In testimony whereof I have signed my name to this specification, in the presence of two subscribing witnesses, this 30th day of November, A. D. 1896. 35

HENRY M. COLLESTER.
